Design No. 6,796, dated August 5, 1873

UNITED STATES PATENT OFFICE.

ALEXANDER T. WEBSTER, OF NEW BRUNSWICK, NEW JERSEY, ASSIGNOR
TO NEW BRUNSWICK CARPET COMPANY, OF SAME PLACE.

DESIGN FOR CARPET.

Specification forming part of Design No. **6,796**, dated August 5, 1873; application filed July 26, 1873.

CASE A.

To all whom it may concern:

Be it known that I, ALEXANDER T. WEBSTER, of New Brunswick, in the county of Middlesex and State of New Jersey, have invented a Design for Carpets, of which the following is a specification:

The nature of my design is fully represented in the accompanying photographic illustration, to which reference is made.

a is a white or light colored ground, having dark sprigs, twigs, or branches *b* thereon, with dark clusters, at *c*, at regular intervals, in the center of which are light-colored spots *d* of irregular form. The clusters *c* are shaded with a color, *e*, a shade lighter than *c*, and on one side the clusters mingle with the twigs or branches *b*, showing the light and dark colors combined.

At regular distances from each other are dark twigs or branches of foliage *f* surrounded by the sprigs *b*, the dark color being more concentrated, and appearing darker on the light-colored ground than the sprigs first mentioned.

The design shows no sharply-defined lines or geometrical figures; but the twigs, spots, and shading named are regularly distributed over the surface, the clusters *c*, spots *d*, and twigs *f* being prominent features.

What I claim as my invention is—

A design for a carpet, as shown and described.

ALEXANDER T. WEBSTER.
